THERMOSTAT HOUSING

Henry Dreyfuss, South Pasadena, Calif., assignor to
Minneapolis-Honeywell Regulator Company, Minne-
apolis, Minn., a corporation of Delaware

Application February 20, 1956, Serial No. 40,239

Term of patent 14 years

(Cl. D52—7)

FIG. 1

FIG. 2

FIG. 3

Figure 1 is a front elevation of a thermostat housing embodying my new design;

Figure 2 is a side elevation of the device shown in Figure 1; and

Figure 3 is a front perspective view of the device shown in Figure 1.

The essential features of the design reside in the full line portions.

I claim:

The ornamental design for a thermostat housing, sub-
stantially as shown and described.
